UNITED STATES PATENT OFFICE

121,141

DESIGN FOR A CHAIR OR SIMILAR ARTICLE

Lewis Larsen, Menominee, Mich., assignor to Heywood-Wakefield Company, Gardner, Mass., a corporation of Massachusetts

Application April 9, 1940, Serial No. 91,559

Term of patent 3½ years

To all whom it may concern:

Be it known that I, Lewis Larsen, a citizen of the United States and a resident of Menominee, county of Menominee, and State of Michigan, have invented a new, original, and ornamental Design for a Chair or Similar Article, of which the following is a specification, reference being had to the accompanying drawing, forming a part thereof, and in which

Fig. 1 is a perspective view of a chair or similar article showing my new design;

Fig. 2 is a view in front elevation, on a scale enlarged over that of Fig. 1, of a fragment of one margin of the chair shown in Fig. 1;

Fig. 3 is a view in rear elevation of that part of the chair appearing in Fig. 2 and

Fig. 4 is a sectional view through the marginal part of the fragment appearing in Fig. 2 as taken on the line 4—4 of said Fig. 2.

This application is a continuation-in-part of my copending design application Ser. No. 83,216, filed February 27, 1939.

The dominant feature of my design is shown in full black lines in the figures.

I claim:

The ornamental design for a chair or similar article, substantially as shown, and described.

LEWIS LARSEN.
